ASH TRAY

Charles Purrington Oakley, Benson, Ariz.

Substituted for abandoned application Serial No. 136,027, January 9, 1947. This application February 2, 1951, Serial No. 14,085.

Term of patent 14 years

(Cl. D85—2)

To all whom it may concern:

Be it known that I, Charles Purrington Oakley, a citizen of the United States of America, residing at Benson, in the county of Cochise and State of Arizona, have invented a new, original, and ornamental Design for an Ash Tray, of which the following is a specification, reference being had to the accompanying drawing, forming a part thereof wherein;

Figure 1 is a top plan view of an ash tray, showing my new design; and

Figure 2 is a side elevation thereof.

The present application is a substitute for my former application for the same design, Serial Number D. 136,027, filed January 9, 1947, now abandoned.

I claim:

The ornamental design for an ash tray, as shown.

CHARLES PURRINGTON OAKLEY.
